UNITED STATES PATENT OFFICE.

JOHN HOGAN, OF BOSTON, MASSACHUSETTS.

FIREMAN'S BELT.

1,010,763.

Specification of Letters Patent.

Patented Dec. 5, 1911.

Application filed January 10, 1911. Serial No. 601,914.

To all whom it may concern:

Be it known that I, JOHN HOGAN, a citizen of the United States, residing at Boston, county of Suffolk, and State of Massachusetts, have invented an Improvement in Firemen's Belts, of which the following description, in connection with the accompanying drawing, is a specification, like characters on the drawing representing like parts.

This invention relates to firemen's belts and has for its object to provide a belt of this nature which is provided with novel means that can be used for attaching the belt to a ladder so that the fireman may have the use of both hands while on the ladder and which can also be used for supporting a hose, carrying fire extinguishers, and for various other purposes.

My invention will first be described and then the novel features thereof will be pointed out in the appended claims.

Referring to the drawings, Figure 1 is a view of a belt embodying my invention; Fig. 2 is an enlarged section on the line $a-a$, Fig. 1; Fig. 3 is an enlarged section through the hook at the end of the strap; Fig. 4 shows the manner in which the belt is used for securing a fireman to a ladder.

3 indicates a belt of any suitable material preferably of canvas which is adapted to encircle the body of the fireman, said belt being provided with a buckle 4 and a tab 5 to be inserted in the buckle.

6 designates a strap which is fastened at one end to the belt and is provided at its other end with a hook 17 that is adapted to hook into an eye or ring 18 carried by the belt. The strap 6 can be made of any suitable material, but I will preferably use canvas for this purpose, and in order to make a strong and solid connection between the strap 6 and the belt 3 I propose to employ the construction shown in Fig. 2 wherein

45 the strap 6 is carried up on the inside of the belt 3 and then is folded over the top edge of the belt 6 at 7 and passed down the outside of the belt, as shown at 8, and then is folded over the lower edge of the belt at 9

50 and passed up between the belt and the body of the strap, as shown at 10. The different layers or plies of strap are fastened to the belt by suitable rivets 11 and a strong and reliable connection is thus made. If desired I may employ a plate 12 of metal on the exterior of the portion 8 of the strap and an-

other plate 13 on the inner side of the strap 6, and these plates may conveniently be made from a piece of metal bent into U-shape. The rivets 11 are shown as passing through both the plates 12 and 13 and through the belt and folds in the strap. The ring 18 is shown as inserted between the portion 8 of the strap and the belt and situated between the rivets 11. This construction, therefore, not only makes a strong connection between the strap 6 and the belt, but also provides a means for securing the ring 18 to the belt.

The hook 17 is provided with an eye 14 to which the strap 6 is fastened, and in making this connection I propose to pass the strap through the eye, as shown at 15, and thence extend the portion 16 of the strap parallel to the body thereof and then bend 75 the strap on itself, as at 19, and extend the portion 20 thereof along adjacent the body of the strap 6 and around through the eye 14, as at 21, and then have the end 22 of the strap inserted between the plies 16 and 20. 80 These layers or plies of strap where they are folded on each other may be secured together by stitches 23, rivets 24, or both as desired. This makes an extremely strong connection which will withstand any weight that the 85 strap 6 is capable of bearing.

The hook 17 which is in the nature of a snap hook is of novel construction. Said hook is provided with the jaw 25 pivoted to the body thereof, as at 26, and having integral therewith a lug or rest 27 that engages a follower 28 confined in a bore or chamber 29 in the shank of the hook, and rests against a spring 30 located in said bore, said spring resting at one end against a plug 31 95 which is screw-threaded into the bore. The advantage of this construction is that the hook has no projecting parts liable to catch in the clothing.

The body of the belt is provided with a 100 holder 32 for carrying a spanner or other suitable implement and may also be provided with a pocket 33 as usual in devices of this class.

Fig. 4 shows the way in which the belt 105 may be used for tying a fireman to a ladder. In said figure the fireman is shown at 34 and the ladder at 35. The strap 6 is passed around one of the rounds of the ladder and the hook 17 is hooked into the eye 110 18, thus firmly securing the fireman to the ladder and permitting him the use of both

hands. The strap 6 and its hook can also be used for assisting the fireman in carrying a hose to the top of the building, or the hook may be fastened to a fire extinguisher or 5 some other article which the fireman wishes to carry up the ladder.

A belt embodying my invention can be inexpensively made and is a very great convenience to firemen.

10 It will be noted that the jaw 25 of the hook is in alinement with the nose 34 so that when the hook is closed, as seen in Figs. 1 and 3, the sides thereof are perfectly smooth. This permits the device to be used 15 by a fireman in lowering himself down a life line, for the line may be wound around one side of the hook a sufficient number of times to generate a proper amount of friction, and as the hook has no shoulders or 20 projections the rope will slide freely thereover as the fireman slides down it.

Having fully described my invention, what I claim as new and desire to secure by Letters Patent is:—

25 1. The combination with a belt, of a strap 6 having a hook at one end thereof, said

strap passing up on the inside of the belt, then over the top thereof and then over the outside and the end of the strap being situated between the body thereof and the inside of the belt, rivets or fastening means extending through the strap and belt, and a ring secured between the outer face of the belt and strap. 30

2. The combination with a belt, of a ring 35 overlying the upper face thereof, a strap 6 having a hook at one end thereof, said strap passing up on the inside of the belt, then over the top and down on the outside thereof through the ring, the end of the strap 40 being situated between the inside face of the belt and the body of the strap, metal plates overlying the portions of the strap which pass around the belt, and rivets extending through said metal plates, strap and belt. 45

In testimony whereof, I have signed my name to this specification, in the presence of two subscribing witnesses.

JOHN HOGAN.
